UNITED STATES PATENT OFFICE.

FRANZ HUGO THUEMLER, OF CHICAGO, ILLINOIS.

DESIGN FOR A BOTTLE.

SPECIFICATION forming part of Design No. 21,736, dated July 26, 1892.

Application filed January 18, 1892. Serial No. 418,503. Term of patent 7 years.

To all whom it may concern:

Be it known that I, FRANZ HUGO THUEMLER, a subject of the Emperor of Germany, residing at Chicago, in the county of Cook and 5 State of Illinois, have invented and produced a new and original Design for Bottles, of which the following is a specification, reference being had therein to the accompanying drawing.

This invention relates to a new and original 10 design for flasks or bottles.

The accompanying drawing is a side elevation of a bottle embodying my design.

The said drawing illustrates a bottle the 15 exterior contour and configuration of which represents a trumpet and handle. The upper or body portion of the trumpet is represented

as having straight sides which merge into the inwardly-curved sides of the base. There is also a representation of a cord coiled around the body of the bottle and terminating in 20 tassels at the base thereof. I thus provide a bottle that presents a novel, pleasing, and unique effect upon the eye.

I claim as my invention—

The design for a flask or bottle, substantially as shown and described. 25

In testimony whereof I affix my signature in presence of two witnesses.

FRANZ HUGO THUEMLER.
